UNITED STATES PATENT OFFICE

2,237,356

INSECTICIDE

David R. Merrill, Long Beach, Calif., assignor to
Union Oil Company of California, Los Angeles,
Calif., a corporation of California

No Drawing. Application May 2, 1939,
Serial No. 271,283

7 Claims. (Cl. 167—30)

This invention relates to insecticides, particularly to insecticidal sprays such as fly sprays, cattle sprays and the like wherein the active agent is contained in a carrier or solvent, and it also relates to insecticides in which the active agent is carried on an inert or active dry carrier or dust, or also in unctuous form.

The object of the present invention is to provide insecticides of the type indicated containing as an important active constituent a material of greater repellent value than heretofore employed in commercial uses of the indicated type, and wherein the repellent material employed in the various carriers is non-volatile, non-subliming and stable.

According to this invention, the active constituent is an alkyl ester of a terpene dicarboxylic acid, and specifically the invention involves an alkyl ester (e. g. diethyl ester) of a polybasic acid of terpene origin produced from an anhydride known as 3-isopropyl-6-methyl-3,6-endoethylene- Δ^4 tetrahydro phthalic anhydride. Since the anhydride actually employed as the starting material is a commercial synthetic product containing polymeric materials, the ester product also contains polymeric materials in minor quantities. This material also has the characteristic of increasing toxic action of other materials which have in themselves toxic action, such as pyrethrin, derris extracts and kindred organic toxic materials usable in sprays of this type.

The invention resides in the use of such alkyl ester from said substituted polybasic acid anhydride as an insecticide. The invention also resides in a mineral oil fraction as a carrier for said alkyl ester. Such a fraction may be kerosene or the like where the material is to be used for fly sprays for example, or it may be a less volatile heavier material commonly known as mineral spray oil, or other appropriate fraction. The invention also resides in the use of said modified terpene esters in any other appropriate carrier such as a dust or unctuous body. Also the invention resides in compositions containing the mentioned esters which also additionally contain toxic agents such as pyrethrum and the like whose toxic action is increased through the presence of said esters.

The alkyl tetrahydro phthalic anhydride employed for production of the esters of this invention may be obtained on the market under the trade name "Petrex" manufactured by Hercules Powder Company, this material also containing a small quantity of polymeric materials. The essential constituent is the phthalic anhydride sub-

stitution product mentioned which is a synthetic, resinous, polybasic acid anhydride of terpene origin. This anhydride is substantially non-volatile, does not sublime on heating and retains its pale yellow color at elevated temperatures. It possesses an acid number of about 530, has a softening point of 40° F. to 50° F., a specific gravity of 1.15, and is soluble in alcohols, various drying oils, acetates, coal tar hydrocarbons, mineral spirits and other petroleum fractions such as kerosene, mineral spray oils and similar light mineral oil fractions adapted to insecticidal uses.

Said substituted phthalic anhydride appears to be 3-isopropyl-6-methyl-3,6-endoethylene- Δ^4 -tetrahydro phthalic anhydride, having the following indicated structure, and an ester of the invention has the corresponding indicated structure where R is an alkyl group:

The above materials are of terpene origin as is apparent from a well known terpene ($C_{10}H_{16}$) having the structure:

The commercial "Petrex" described is used as the starting material for the terpene esters required for the present invention. Any suitable method of esterification may be employed. A satisfactory procedure is represented by the following example. 800 grams "Petrex" was added to 800 ml. of absolute ethyl alcohol together with 175 ml. of 94% sulfuric acid as a catalyst. The mixture was agitated at 185° F. to 195° F. for one hour. After standing for several hours (which apparently is not necessarily required), the mixture was washed twice with water to remove the

acid and excess alcohol and yielded a product containing a mixture of di-esters and mono-esters of said terpene dicarboxylic acids.

Either these mixed esters may be used as such, or they may be separated and used separately. For example, the mono-ester may be extracted from the di-ester by using a solution of about equal parts of alcohol and water containing 6% sodium hydroxide. The separated solution contains the mono-ester which may be in turn separated by acidifying the extract and washing. The di-ester, which did not enter into the extracting solution, was recovered simply by washing with water in the cold. The di-ester product is a yellowish to orange liquid of high viscosity approximating that of heavy lubricating oil. It has an acid number of 0.72 and a saponification number of 306. The mono-ester is normally considerably more viscous than the di-ester and is nearly solid. The boiling point of both esters is above 400° F. The acid number of the mono-ester is considerably higher than that of the di-ester being about 154. Both are soluble in alcohols, mineral spirits, mineral oil fractions and the like and, being highly stable, are well adapted to the present uses, especially in view of the fact that they have high repellent values for insecticidal purposes. By somewhat similar procedures, obvious to the skilled chemist, other alkyl esters of the lower alcohols also may be produced and employed, such as the lower alkyl esters methyl, propyl and butyl esters.

The above described alkyl ester products of the indicated terpene dicarboxylic acid which are herein sometimes referred to as "Petrex" esters for convenience, are added to various petroleum oils suitable for individual purposes, in concentrations varying from about 1% to about 10%. Perhaps a good general average is in the vicinity of 3% to 5% based on the oil fraction employed. For the purpose of fly sprays an appropriate cut in the kerosene range, which may be if desired either in the nature of a light kerosene cut or a heavy kerosene cut, may be employed. For other uses it may be desirable to employ heavier materials such as spray oils, for example where making up cattle sprays. Mineral spray oils are well known in the agricultural industry. They are lighter than ordinary light lubricating oils, although they have lubricating characteristics, and possess viscosities in the order of about 50 to 125 seconds Saybolt Universal at 100° F. Such oils for horticultural uses commonly possess highly unsulfonatable residues in the neighborhood of

90% or better, which residues are commonly referred to as deOng number, for example 90 deOng. However, oils in these viscosity ranges may possess lower unsulfonatable residues, for example in the range of 60 to 70 deOng or even lower or higher as uses may permit.

As a specific example, 5% of ethyl "Petrex," as above described, employed in a kerosene type cut in the range commonly used for fly sprays has been employed and found to be highly preferable as a repellent to all other types of synthetic material used in the same concentration.

In addition to using the "Petrex" ester in petroleum fractions as described, it may be desirable to add other insecticidal constituents such as pyrethrum, or derris or cube extracts, or alkyl thiocyanates, and the like. In some instances it may be preferable to prepare the insecticide as a dust in which case it may be carried in an inert carrier such as diatomaceous earth or it may be carried on an active carrier such as powdered pyrethrum flowers or ground derris root or the like. Again the "Petrex" alkyl esters may be carried in an unctious type carrier such as lanolin or other greasy or pasty material.

It is to be understood that these disclosures are given as illustrative of the generic invention within the scope of the appended claims, rather than as limiting thereof.

I claim:

1. An insecticide comprising a lower alkyl ester of 3-isopropyl 6-methyl 3,6-endoethylene Δ^4 -tetrahydro-phthalic acid.

2. An insecticide according to claim 1 wherein the ester is one of the class consisting of methyl, ethyl, propyl and butyl esters.

3. An insecticide according to claim 1 wherein the ester is the di-ethyl ester.

4. An insecticide according to claim 1 including a mineral oil fraction as a carrier.

5. An insecticide according to claim 1 including a carrier and wherein the ester is one of the class consisting of methyl, ethyl, propyl and butyl esters.

6. An insecticide comprising a slowly volatilizing petroleum fraction, and a low alkyl ester of 3-isopropyl 6-methyl 3,6-endoethylene Δ^4 -tetrahydro-phthalic acid.

7. An insecticide according to claim 6 wherein the ester is the ester of an alcohol of the group consisting of methyl, ethyl, propyl and butyl alcohols.

DAVID R. MERRILL.
